Primary Examiner — Vy N Koenig(74) *Attorney, Agent, or Firm* — Che-Yang Chen; Law Office of Michael Chen(57) **CLAIM**

The ornamental design for a ball chair, as shown and described.

DESCRIPTION

FIG. 1 is a perspective view of a ball chair showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the ball chair that form no part of the claimed design.
